MATTRESS

Alfred Klazkin, Brooklyn, N. Y.

Application March 25, 1943, Serial No. 480,426

2 Claims. (Cl. 5—345)

My invention relates to an improvement in mattresses and its novelty consists in the combination, adaptation and arrangement of parts as will be more fully hereinafter pointed out.

The inner spring mattress was a definite advance over the old solid hair or fibre mattress because of the approach to conforming of the inner spring mattress to the body of the person lying on it. But the inner spring mattress has several important and inherent defects. The springs are unevenly spaced and therefore uneven in spring support and become detached and therefore topple over sidewise and cause a greater unevenness which is most uncomfortable. The metal of said springs also sweats under regular conditions of use and rusts and rots the fastenings and fabric in contact with them.

My invention overcomes all of these weaknesses inherent in the inner spring mattress and also furnishes for the first time a mattress that is always uniformly and evenly springy and resilient throughout its entire body. This is because an absolutely even spring tension is always maintained throughout its entire body. The metal springs common to the inner spring mattress are eliminated in my mattress and thereby the weaknesses and defects of said metal springs are not found in my mattress.

My invention also avoids the use of a substantial amount of critical war material by eliminating the use of steel springs and this is important during this present Global War.

Referring to the drawing.

Fig. 1 is a perspective of my mattress with a portion of the outer covering cut away to show the inner construction;

Fig. 2 is a longitudinal cross section of my mattress with one type of tensioning device;

Fig. 3 is a front view of my mattress with a portion cut away to show a second type of tensioning device;

Fig. 4 shows the portion of my mattress cut away in Fig. 3;

Fig. 5 is a side enlargement of Fig. 4 showing the inner connection in dotted line.

In the drawing, 6 are two side wooden frame members having a pair of wooden end members 7 secured together by nails or screws in the usual well known manner at the joining corners to form a frame 8.

Over the top and bottom of said frame 8 are tightly stretched and secured cross webbing strips 9 which are fastened over the upper and lower edges of the side members 6 at 10 and longitudinal webbing strips 11 are stretched and fastened

over the upper and lower edges of the end members 7 being fastened at 12 and also being mounted so as to be interwoven with the cross strips 9.

One set of ends of the longitudinal strips 11 5 may be secured over the edges of a tensioning board 13 mounted adjacent one end 7 of frame 8 by means of guide rods 14 rigidly secured to 7 and passing through aligning holes in 7 and by three tensioning screw bolts 15 having three screw heads 15a encased in metal casings 15b embedded in the tensioning board 13 so that the heads of said bolts 15 are accessible externally and passing through 13 and an embedded threaded nut 16 in end 7 whereby the turning of said screw bolts 15 by means of regular slotted heads will as desired vary the relative position of 13 15 from 7 thereby adjusting the tension of said longitudinal strips 11 fastened thereto as may be desired.

20 This tensioning form is shown in Figures 1 and 2 and another form for accomplishing this same function is shown in Figs. 3, 4 and 5.

In the tensioning form shown in Figs. 3, 4 and 5 a pair of rollers 17 and 18 are rotatably mounted in brackets 19 and 20 a pair of which are rigidly secured through 7' at 21 and 22 at each end of 7' and the ends of the longitudinal strips 11 are secured to said rollers 17 and 18 so as to be rolled thereon for tensioning.

30 Said rollers 17 and 18 have handles 23 and 24 rigidly secured to their outer ends and pawls 25 and ratchets 26 of usual construction are mounted to operate on said rollers 17 and 18 just inside of said handles 23 and 24 so as to hold said rollers against the tension of strips 11. Also the ends of the longitudinal strips 11 pass over and around guide rods 32 which are rigidly mounted between the sides 6.

Around said frame 8 and the parts as described 40 mounted therein is placed a filling of cotton, sisal or hair 27 over all of which is secured a ticking 28 in the usual manner with tufting obtained by stitched tabs 29 and looped handles 30 are secured to the stitched edges 31 for the ready handling and turning over of said mattress.

In the use of my mattress it will be found that 45 because of the uniform tension of the interlaced strips 9 and 11 throughout the entire top and bottom surfaces of the mattress that on either side of the same as the user lies on same the mattress will actually conform perfectly to the form of the user's body.

If any of the strips 9 and 11 tend to sag 50 because of long use or abuse this can be readily adjusted by adjusting the screw bolts 15 in the

construction of Figures 1 and 2 by means of a screw driver inserted through grummets 33 mounted in the side of ticking 28 adjacent the tensioning board 13. The adjustment of the tension of strips 11 in this manner will also correct the tension of strips 9 because they are interlaced with 11.

In the structure shown in Figs. 3, 4 and 5, the turning of the handles 23 and 24 will adjust the tension of strips 11 and thereby also strips 9 and the pawls 25 will lock in the usual manner in ratchets 26 to hold the rotated rollers 17 and 18 in tightened position.

Many variations may be made in the material used and in the adaptation and arrangement of parts without departing from the spirit and intent of my invention and such variations are comprehended in the scope of the specification and claims of this application.

What I claim is:

1. In a mattress, the combination of an oblong rigid frame, cross interlacing webbing strips secured crosswise and lengthwise to both the top and bottom of said frame and a single means for increasing the tension of the lengthwise webbing elements uniformly on the top and bottom respectively at one end, comprising two rollers mounted inside one end of said frame, each roller

having one end projecting from the frame with the other end disposed interiorly thereof to each of which one set of lengthwise webbing elements is secured, turning handles secured to the projecting ends of said rollers, a ratchet and a pawl mounted on said frame adjacent said handles for securing said rollers against release as the lengthwise elements are tightened thereby.

2. In a mattress, the combination of an oblong rigid frame, cross interlacing webbing strips secured crosswise and lengthwise to both the top and bottom of said frame, layers of filling mounted around said frame and flexible strips, a mattress ticking secured in a fixed position around said filling and a single means for increasing the tension of the lengthwise webbing elements uniformly on the top and bottom respectively at one end comprising two rollers mounted inside one end of said frame, each roller having one end 10 projecting from the frame with the other end disposed interiorly thereof to each of which one set of lengthwise webbing elements is secured, turning handles secured to the projecting ends of said rollers, a ratchet and a pawl mounted on said frame adjacent said handles for securing said rollers against release as the lengthwise elements are tightened thereby.

ALFRED KLAZKIN.
